UNITED STATES PATENT OFFICE.

ALFRED P. LAFLAM, OF BURLINGTON, VERMONT.

ATTACHMENT FOR COMBING MACHINES.

Application filed June 10, 1927. Serial No. 197,807

My present invention relates to combing machines, and is particularly directed to a selvage guide for the detaching rolls of such machines, and has for its object the provision 5 of a rigidly secured guide for each side of the machine that flexibly engages the roll a little above the center thereof to guide the cotton as it passes above the two lower and below the two upper rolls to prevent the cotton 10 winding itself around the rolls and breaking the sliver which automatically stops the machine and causes damages and delays.

Specifically the improvement comprises angle plates of suitable metal to insure the 15 rigidity thereof and which plates are notched for the reception of bolts whereby the said plates may be adjustably but rigidly fixed on the comber, the vertical arm of each plate being notched and the portion thereof above 20 the notches having its outer edges rounded to form a guide, the vertical arm of the plate receiving therein binding means for a vertically adjustable angularly disposed wiper holder removably supported on the said vertical 25 arm of the support that contacts with the detaching roll of the machine.

The drawings illustrate a satisfactory embodiment of the improvement and wherein:

Figure 1 is a view illustrating my invention in applied position.

Figure 2 is a perspective view of the improvement.

Figure 3 is a front elevation thereof.

Figure 4 is a plan view of the blank from 35 which the holder for the leather wiper strip is formed.

In Figure 1 of the drawings, the improvement is disclosed in applied position upon the type of combing machines known to the trade 40 as the Whitin and Nasmith machine. As the constructions of these machines are well known in the art, a detail description thereof and the working of the parts constituting the same is not believed necessary. In the drawings 45 the comber cylinder is indicated by the numeral 1, the bottom nipper plate by the numeral 2 and the bottom detaching roll by the numeral 3. As my improvement is designed for contacting engagement with the 50 detaching roll 3 to serve as a guide for the cotton selvage therefrom, and as the construction and operation of this type of machines, as above stated, is well known in the art, reference to the remainder of the machine 55 is not believed necessary.

It will, of course, be understood that one

of these devices is placed at each side of the machine with the wiper parts of the two devices engaging the end parts of the detaching roll 3 but as the devices are of the same construction but one of them will be described. Each device comprises a frame or support composed of a rectangular metal plate whose horizontal portion is indicated in the drawings by the numeral 4 and whose vertical portion by the numeral 5. The horizontal portion 4 from the end thereof is formed with a longitudinal slot 6 and through this slot there is passed a bolt member 7 engaged by a nut 8 which holds the device on the comber. The vertical arm 5 of the support is notched, as at 7', and upward of the notch the outer edge of the arm is rounded, as at 9, to provide selvage guides. The notch enables the edge to be bent into rounded shape. The angle or vertical arm of the support, inward of the notch 7' is provided with spaced aligning somewhat elongated openings 10, and passing through these openings there are the shanks of short headed bolts 11 screwed 80 through openings 12 in the depending plate or skirt 13 of a holder member 14. As disclosed by Figure 4 of the drawings, the holder member 14 may be constructed from a substantially T-shaped strip or member, and the upper portion thereof is bent over the body in a line with its lower edge, and the projecting portions are then bent upon themselves and extended inwardly over the right- 85 angular part 15 of the holder thus provided. This right angular portion 15, with its bendable lower portions or arms 16 afford a pocket 90 for a leather strip 17, and this strip contacts with the roll 3 at a point above the axial center thereof. The holder 14 is constructed of 95 some suitable strong metal, as is the frame or support that constitutes the right angular arms 4 and 5.

The leather wiper member 17 is at all times in contact with the periphery of the roll 3 to 100 effectively wipe the roll and to direct selvage therefrom over the guide flange 9 of the support.

The simplicity of the improvement and the advantages thereof will, it is thought, be perfectly apparent to those skilled in the art to which such invention relates, it being obvious that the support is adjustably sustained upon the comber and that the holder 14 is likewise adjustably sustained upon the support. When 105 in operation the device affords a rigid structure and will effectively prevent the selvage 110

winding around the roll and stop the operation of the comber.

Having described the invention, I claim:—

1. In a comber and in combination with the detaching rolls thereof, a support comprising a rightangular member having its horizontal arm adjustably but rigidly secured on the frame of the comber, a holder removably and vertically adjustably secured on the vertical part of the support, and a leather strip designed to be received in and supported by the holder and engaging one of the said rolls.
2. In a comber machine and in combination with the detaching rolls thereof, a supporting member of rightangular shape whose horizontal part is of a greater length than its vertical part and which horizontal part is provided with an elongated slot for the reception of securing means, the vertical part having its outer edge notched and the corner thereof above the notch rounded to provide a

guide, said vertical part having spaced elongated openings therethrough, bolts having threaded shanks passing through the openings, a holder comprising a pocket having a rightangular skirt on the inner edge thereof and through which the bolts are screwed and said holder designed for the reception of a leather wiper member which engages one of the rolls.

3. In a comber machine, and in combination with its detaching rolls, a support connected with a part of the machine and extending between two pairs of said rolls, said support having a guiding part thereon, a holder vertically adjustable on the support below the guiding part thereof and having a horizontal part and a wiper member of flexible material carried by said horizontal part and engaging one of the rolls.

In testimony whereof I affix my signature.

ALFRED P. LAFLAM.
